DESIGN FOR A BELL BRACE FOR A SAXOPHONE

Earl J. Gillespie, Elkhart, Ind., assignor to The
Martin Band Instrument Company, Elkhart,
Ind., a corporation of Indiana

Application February 23, 1945, Serial No. 118,102

Term of patent 14 years

(Cl. D56—1)

To all whom it may concern:

Be it known that I, Earl J. Gillespie, a citizen of the United States, residing at Elkhart, in the county of Elkhart and State of Indiana, have invented a new, original, and ornamental Design for a Bell Brace for a Saxophone, of which the following is a specification, reference being had to the accompanying drawing, forming a part thereof.

In the drawing:

Figure 1 is a side perspective view of a bell brace for a saxophone showing my new design,

with the bell of the saxophone and a part of the tubular body shown in dotted lines for illustrative purposes only;

Figure 2 is a sectional view taken on the line 2—2 of Figure 1; and

Figure 3 is a perspective view of the bell brace shown in Figures 1 and 2.

I claim:

The ornamental design for a bell brace for a saxophone, substantially as shown and described.

EARL J. GILLESPIE.
